DESIGN FOR A COMBINED FISHING REEL
AND ROD SEAT

Edwin P. Hurd, Detroit, Mich., assignor to Hurd
Lock and Manufacturing Company, Detroit,
Mich., a corporation of Michigan

Application October 11, 1947, Serial No. 141,873

Term of patent 14 years

(Cl. D31—4)

To all whom it may concern:

Be it known that I, Edwin P. Hurd, a citizen of the United States, residing at Detroit, Wayne County, Michigan, have invented a new, original, and ornamental Design for Combined Fishing Reel and Rod Seat, of which the following is a specification, reference being had to the accompanying drawings forming a part thereof, in which

Fig. 1 is a side elevation of a combined fishing reel and rod seat, showing my new design;

Figs. 2 and 3 are top and bottom elevational views, respectively, and

Figs. 4 and 5 are rear end and front end elevations, respectively, of the combined fishing reel and rod seat shown in Fig. 1, Fig. 4 being taken substantially on the line 4—4 in the direction of the arrows, Fig. 1; Fig. 5 being taken substantially on the line 5—5 in the direction of the arrows, Fig. 1.

The opposite side elevation of the combined fishing reel and rod seat is substantially the same as that shown in Fig. 1, except for the omission of the reel crank and knob.

I claim:

The ornamental design for a combined fishing reel and rod seat, as shown and described.

EDWIN P. HURD.
